Thos. Eichens, Esq.
Attorney

UNITED STATES PATENT OFFICE.

JOHN K. SHAW, OF MINNEAPOLIS, MINNESOTA, ASSIGNOR TO B. G. DAHLBERG, OF ST. PAUL, MINNESOTA.

SIDE WALL AND CORNER FOR BUILDINGS.

1,313,421.

Specification of Letters Patent. Patented Aug. 19, 1919.

Application filed May 23, 1918. Serial No. 236,162.

To all whom it may concern:

Be it known that I, JOHN K. SHAW, a citizen of the United States, residing at Minneapolis, in the county of Hennepin and State of Minnesota, have invented certain new and useful Improvements in Side Walls and Corners for Buildings; and I do hereby declare the following to be a full, clear, and exact description of the invention, such as 10 will enable others skilled in the art to which it appertains to make and use the same.

This invention relates to the treatment of the corners of buildings with the material known as "insulite" and has for its object to 15 improve the appearance as well as the durability of said corners in a manner more efficient and less costly than has been heretofore proposed.

With these and other objects in view the 20 invention consists in the novel details of construction and combinations of parts more fully hereinafter disclosed and particularly pointed out in the claims.

Referring to the accompanying drawings 25 forming a part of this specification in which like numerals designate like parts in all the views—

Figure 1 is an elevational view of a corner of the building treated in accordance with 30 this invention;

Fig. 2 is a sectional view on the line 2—2 of Fig. 3, looking in the direction of the arrows;

Fig. 3 is a sectional view on the line 3—3 35 of Fig. 2, looking in the direction of the arrows; and—

Fig. 4 is an elevational view of the metal corner clip employed in this invention.

1, 2 and 3 indicate the upright timbers 40 constituting the main corner supports of a building, 4 and 5 indicate the usual wooden side wall material employed in such buildings and 6 and 7 indicate slabs or boards made of the material well known on the 45 market as "insulite." This "insulite" material is a paper board material made of fibers obtained from wood but it differs from the ordinary paper board in that it is exceedingly light and is possessed of an unusual 50 high heat insulating quality. That is to say, it resembles cork in many of its physical qualities it having a specific gravity of say not more than .3 or .4 and it often has a specific gravity as low as .2 or lower.

55 It is made of at least three different classes

of fibers. The one class is so coarse that they really constitute slivers in that they are say often one eighth of an inch wide, and one half to one inch in length. The second class of fibers are more or less string like in that they are say from one thirty second of an inch to one sixty fourth of an inch wide, and are from one half to one inch, or two inches long.

The third class of fibers are more or less hairlike in that they are from say one hundredth to one two hundredth of an inch in diameter and are say from one half inch or less in length.

In addition to these various classes of 70 fibers, the mass is mixed with a considerable quantity of ordinary sulfite fibers employed in paper making. The result of felting together into a homogeneous mass fibers having such great variations in their coarseness is to make a body having great porosity, 75 high heat insulating qualities, and one well adapted for the outer covering of buildings. On the other hand, the extreme edges of the boards or slabs made from this material are 80 more or less fragile, and therefore, it is desirable to protect them from the weather and from rough usage.

Owing to this fragility and to the unusually porous nature of the material said edges, 85 unless special precautions are taken, are unsuited for being fastened, like other boards, on the sides of houses; and further, even when fastened in place they will rapidly deteriorate under the influence of the 90 weather, unless precautions are taken to protect them.

Accordingly, the boards of "insulite" such as 6 and 7 are laid over each other as illustrated in Figs. 1 and 3, and their extreme 95 meeting edges such as 8 are covered by a metal piece indicated as at 9. This metal piece is conveniently struck up by any suitable dies, it is provided with faces 10 and 11 at substantially right angles to each other, and each face is provided with a lip such as 12 and 13, which extends at substantially right angles to the faces 10 and 11 all as will be clear from Fig. 2. The said lips 12 and 13 are conveniently serrated or provided 100 with projections as best shown in Fig. 4, in order to facilitate the biting in of the pieces 9 as will be clear from the drawings.

The strips or members 9 are of a length 110 equal to the width of the insulite boards,

their serrations on their lips 12 and 13 extend the whole length of said strips, and at one end the sides of said strips are bent inward to form the additional pairs of lips 14. These said lips 14 are coextensive with the sides 10 and 11 as shown, and are therefore disposed at right angles to each other as will be clear from Figs 1 and 4. They extend underneath and protect the bottom edges 16 of the "insulite" boards 6 and 7 as will be clear from said drawings.

It will, therefore, be observed that the members 12 and 13 bite into and secure a firm hold on the porous body of the "insulite", that the two walls 9 and 10 disposed at right angles to each other, effectually inclose and protect from the weather the rough and freshly cut porous and fragile edges of said "insulite", and that the underlying members 14 still further protect and secure the extreme side edges of said insulite boards 6. The entire structure results in a joint which has shown itself to be efficient and satisfactory in practice.

Since the boards 6, for example, overlap each other as best illustrated in Fig. 3, there are left triangular spaces between said boards 6, and the inner side wall material 4. In order to close up all cracks or spaces of this kind, I preferably employ the wedge shaped pieces 17 which may be made of wood, of "insulite" or of other material, but of course, these spaces may be left open if it is so desired.

After the construction above disclosed has been provided the parts are firmly nailed together or otherwise secured in any suitable manner. On the interior of the building, I provide when desired, additional slabs

or boards of "insulite" material indicated 40 at 19 and 20, the extreme edges of which fit in between the edges of the members 1 and 3 which are offset for this purpose as best disclosed in Fig. 2. After the slabs 19 and 20 have been thus placed, any convenient plastic material, such as plaster 21 may be applied directly to the "insulite" and thus the house is effectually sealed with an air space 22 between its inner and outer walls.

It is obvious that those skilled in the art may vary the details of construction, as well as the arrangement of parts without departing from the spirit of the invention, and therefore, I do not wish to be limited to the above disclosure except as may be required by the claim.

What I claim is:—

In a building the combination of corner supports; a side wall joined to said supports; a second side wall joined to said supports and making an angle with said first named side wall; a set of overlapping porous insulite boards having fragile edges overlying one of said side walls; a second set of overlapping insulite boards overlying said second side wall; angular metal members of a length equal to the width of said boards having serrations from end to end on each of their side edges, entering said boards near their meeting edges, and overlying, concealing and protecting said edges, said metal members also provided with inturned lips at one end which underlie and protect the lower side edges of said boards, substantially as described.

In testimony whereof I affix my signature.
JOHN K. SHAW.
